UNITED STATES PATENT OFFICE.

HENRY B. GORTON, OF FRIENDSHIP, NEW YORK, ASSIGNOR OF ONE-HALF
TO EMMIT G. LATTA AND ADRIAN C. LATTA, BOTH OF SAME PLACE.

GUN.

SPECIFICATION forming part of Letters Patent No. 417,241, dated December 17, 1889.

Application filed August 9, 1886. Serial No. 210,410. (No model.)

To all whom it may concern:

Be it known that I, HENRY B. GORTON, of Friendship, in the county of Allegany and State of New York, have invented a new and 5 useful Improvement in Guns, of which the following is a specification.

This invention relates to an improvement in breech-loading guns, and has for its principal object to provide an ordinary breech-loading gun with a breech-loading rifle, which can be readily attached to the gun without altering the construction of the latter or interfering with its use, and which can be as readily detached when not required for use.

15 The invention consists of the improvements which will be hereinafter described, and pointed out in the claims.

In the accompanying drawings, consisting of two sheets, Figure 1 represents a side elevation of a breech-loading double-barrel gun provided with my improved rifle. Fig. 2 is a bottom plan view, and Fig. 3 is a longitudinal sectional elevation, thereof. Fig. 4 is a top plan view of my improved rifle detached 25 from the gun. Fig. 5 is a perspective view of the parts for operating the firing mechanism of the rifle. Figs. 6, 7, and 8 are cross-sections in lines xx , yy , and zz , Fig. 1, respectively. Fig. 9 is a cross-section in line ww , Fig. 1. Fig. 10 is a bottom plan view of 30 the rifle, showing the breech open to receive the charge. Fig. 11 is a perspective view of the rear end of the holder and stock of the detachable barrel. Fig. 12 is a top plan view 35 of the locking-lever of the removable barrel.

Like letters of reference refer to like parts in the several figures.

A represents the stock, A' A^2 the barrels, A^3 A^4 the hammers, a a' the triggers, and a^2 40 the trigger-guard, of an ordinary knockdown breech-loading gun.

B represents the detachable rifle-barrel arranged on the under side of the gun-barrels A' A^2 and having its breech fitted in a receiver or holder B' , which is rigidly secured 45 within the fore-stock B^2 . The breech of the rifle-barrel B is capable of sliding lengthwise in the holder B' , and is provided on its under side with a lug b , which moves in a longitudi-

nal slot b' , formed in the under side of the 50 holder.

C represents the lever by which the rifle-barrel is moved lengthwise and which is pivoted with its front end between two lugs c , formed on the holder B' near the front end 55 thereof.

C' is a link which is pivoted with its rear end to the lever C and with its front end to the rifle-barrel B, which latter is provided with a collar c' , to which the link C' is attached. Upon swinging the lever C backwardly or forwardly the rifle-barrel is moved backwardly or forwardly in an obvious manner.

D represents a solid transverse shoulder or 60 breech-block formed in the holder B' in such a position that the open rear end of the barrel B rests against the block D when the barrel is drawn back.

d represents an opening formed in the lever C in such a position as to engage over the breech-lug b of the rifle-barrel when the latter has been drawn back against the breech-block D and the lever C rests against the under side of the holder B' , as represented in 75 Figs. 1 and 2.

E represents a spring-catch whereby the free end of the lever C is secured to the holder B' when the barrel B has been drawn back against the breech-block D. This spring-catch consists of a turn-button e , arranged on the upper side of the lever C and provided with a spring e' , whereby it is held in a locked position. When the lever C is closed, the button e engages in the notch e^2 of a post 80 e^3 , which is secured to the holder B' and projects downwardly therefrom into a hole e^4 , formed in the lever C, as represented in Fig. 12, and in dotted lines in Fig. 2. The stem of the turn-button e extends through the lever C, and is provided on the under side of the latter with a thumb-piece e^5 , by which the button can be turned for disengaging it from the post e^3 . The lever C is countersunk around the thumb-piece e^5 for convenience in 90 operating the latter. It is obvious that any other suitable locking device may be substituted for the turn-button and notched post.

F represents a clamp which embraces the front ends of the barrels A' A², and which carries on its under side a bearing F', in which the front portion of the rifle-barrel B is loosely held, so as to be capable of sliding lengthwise therein.

g represents the pivot or knuckle upon which the barrels turn in knocking down the gun, and which is secured to the front end of 10 the main stock A in the usual manner. The pivot g is provided with a shoulder g', which limits the forward-tilting movement of the barrels, and with side bearings g² in the usual manner.

15 h represents a rearwardly-projecting lug formed centrally on the rear side of the holder B' and engaging over the pivot g, as represented in Fig. 3; and h' h' are curved bearing-surfaces formed on both sides of the lug h and engaging against the side bearings of the pivot g, as represented in Fig. 2.

i represents the hook formed on the under side of the barrels A' A² in the usual manner to engage with the spring-catch at the front 25 end of the ordinary fore-stock. The latter is not shown in the drawings, as it is of ordinary construction and removed from the gun in the usual manner when it is desired to apply the rifle-barrel.

30 J represents a sliding catch applied to the upper side of the holder B' and engaging over the hook i. The shank of the catch J passes through a longitudinal slot j, formed in the holder B', in which slot it can be moved lengthwise to engage it or disengage it from the hook i. The catch J is provided below the slot j with a plate j', which fits between the side walls k k of a longitudinal recess formed in the under side of the holder 35 B' in rear of the breech-block D. The catch J is held from dropping down in the holder by pins k', projecting laterally from the walls k and engaging against the under side of the plate j', as represented in Fig. 10.

40 l represents a turn-button pivoted to the under side of the plate j' near the front end thereof, and whereby the catch J is locked in position when engaged over the hook i by turning the button l, so as to bear against the 45 rear side of the breech-block D, as represented in Figs. 3 and 10. In this position of the parts the rear end of the holder B' is interlocked with the knuckle g and the middle portion of the holder with the hook i by the catch J, whereby the detachable barrel B is 50 firmly secured to the gun in the same manner as an ordinary fore-stock is secured, thereby enabling the detachable barrel to take part in all of the movements of the main barrels 55 A' A² without in anywise interfering with the same. Upon releasing the turn-button l from the breech-block D and moving the catch J forward the rear end of the holder B' can be disconnected from the knuckle g and the barrel B be detached from the gun.

60 M represents the hammer of the detacha-

ble barrel B, pivoted in a horizontal position to the upper side of the holder B', the latter being provided on its upper side with a recess for the reception of the hammer and connecting parts. The fore-stock B² is provided in its side with an opening m, through which the head of the hammer projects far enough to be reached for cocking it, but not so far as to catch in the clothing.

65 n represents the firing-pin arranged at an angle to the axis of the barrel B, with its outer end opposite the face of the hammer M and its inner end passing through an aperture in the breech-block D, so as to strike the center 80 of the cartridge. N represents the mainspring secured with its front end to the holder B', and having its rear end connected with the hammer by a link n'.

O represents the sear pivoted to the holder 85 B' in rear of the hammer, and O' is the sear-spring. The rear arm of the sear is provided with a depending extension O², which plays in an opening O³, formed in the rear portion of the holder B', as represented in 90 Figs. 3 and 4.

p represents the stud, which limits the movement of the mainspring and causes the hammer to rebound to the position shown in Fig. 4, in which the sear rests in the safety-notch. The lock and the metallic receiver 95 B' are nearly concealed by the wooden fore-stock B².

q represents the trigger for the lock of the detachable barrel B, arranged in front of the 100 main trigger-guard a² and pivoted to the under side of a bar Q, which is fitted against the under side of the main stock A and extends forwardly to the rear end of the holder B', as represented in Figs. 1, 2, and 3.

105 R represents the trigger-guard of the trigger q, secured with its upper end to the bar Q and with its lower end to the main-trigger guard a². The lower end of the auxiliary trigger-guard R is provided with a headed shank or hook r, which is inserted in an elongated opening r' in the main-trigger guard by turning the auxiliary guard R on its side, passing the hook through the opening r', then turning the auxiliary guard and the bar 110 Q, to which it is attached, into their normal position, in which the hook r cannot be disengaged from the opening r'. The trigger q is held in its forward position by a spring r², secured to the guard R.

115 S represents a sliding bolt arranged on the upper side of the bar Q, which latter is provided with a longitudinal depression or recess for the reception of the bolt S, as represented in Fig. 5. The rear end of the sliding bolt S is pivoted to the upper arm of the trigger q, while its front end is rounded or oblique and engages against the depending extension O² of the sear, as represented in Figs. 3 and 4. Upon pressing the trigger q backward 120 the bolt S is moved forward and the sear is swung on its pivot and disengaged

from the hammer. When the gun is broken down for loading, the sear O and its depending arm O² move forwardly or away from the front end of the sliding bolt S, so that there is no danger of an accidental discharge of the detachable barrel upon loading or firing either of the main barrels, even when the hammer of the removable barrel is at full cock.

10 When it is desired to load the detachable barrel, the rear end of the lever C is unlocked by releasing the catch E, and the lever is thrown forward, whereby the barrel B is forced forwardly. This movement of the 15 barrel removes the rear end of the barrel from the breech-block D and permits the cartridge to be inserted into the chamber of the barrel or into the cavity of the holder B', as may be preferred. Upon swinging the 20 lever C backwardly and locking it in position, as hereinbefore explained, the open rear end of the barrel B is securely locked against the breech-block D. During this backward movement of the barrel the cartridge is forced 25 into the chamber of the same when the cartridge has been placed in the holder B'. When the lever C is locked in position and the detachable barrel is ready for firing, the lug b of the barrel rests in the opening d of 30 the lever and the rear end of the lever rests against a shoulder formed in the holder B', whereby the barrel is held securely and the link C' is relieved from all strains during 35 the act of firing. The holder B' receives the recoil when the detachable barrel is discharged.

In guns constructed with a permanent full-length rifle-barrel arranged underneath the shot-barrels it has been customary to curve 40 the rifle-barrel to render its front end parallel with the bore of the shot-barrels. This was necessary, owing to the taper of the barrels, when the muzzle of the rifle-barrel was arranged closely to those of the shot-barrels. 45 By my improved construction this is not necessary, as by using a somewhat shorter rifle-barrel which terminates forwardly of the swell at the breech end of the shot-barrels I am enabled to use a straight rifle-barrel and 50 arrange it parallel with the upper barrels and closely against them the whole length of the rifle-barrel.

The construction of the loading and firing devices which I have described and shown is 55 but one of several different devices which may be used, and I do not wish to confine myself to the constructions herein explained.

In some localities it is desirable to be able to hunt either with a shotgun or a rifle, as 60 occasion may arise, and when hunting in such a locality the detachable barrel is attached to the gun, thereby equipping the hunter with a shotgun and rifle without materially increasing the weight of the fire-arm. When 65 the rifle is not required, it is detached and

the ordinary fore-stock is attached to the gun in the usual manner.

It is of course immaterial whether the gun has two permanent barrels or a single permanent barrel, and it is likewise immaterial whether the permanent or the detachable barrel is rifled or not.

I claim as my invention—

1. The combination, with a gun provided with a permanent barrel, of a detachable barrel provided with a firing mechanism attached to the detachable barrel and applied and removed with the same, substantially as set forth.

2. The combination, with a gun provided with a fastening for attaching the fore-stock, of a detachable barrel provided with a stock adapted to be secured to the gun by said fastening, substantially as set forth.

3. The combination, with a gun provided with a fastening for attaching the fore-stock, of a detachable barrel provided with a stock adapted to be secured to the gun by said fastening, and a breech-loading mechanism arranged in said stock, substantially as set forth.

4. The combination, with a gun provided with a fastening for attaching the fore-stock, of a detachable barrel provided with a stock adapted to be secured to the gun by said fastening, and a firing mechanism arranged in said stock, substantially as set forth.

5. The combination, with the double gun-barrels, of a shorter straight barrel located in front of the swell at the breech of the double barrels, whereby the short barrel may be arranged closely to the double barrels and parallel therewith, substantially as set forth.

6. The combination, with a gun provided with permanent barrels, and the detachable barrel capable of longitudinal movement, of the clamp F, applied to the permanent barrels and provided with a bearing F', in which the detachable barrel is supported, substantially as set forth.

7. The combination, with a gun provided with a permanent barrel and having a knuckle g and hook i, of a detachable barrel B and a holder B', provided with a projection h, adapted to be interlocked with the knuckle g, and a sliding catch J, adapted to be interlocked with the hook i, substantially as set forth.

8. The combination, with a gun provided with a permanent barrel and a detachable barrel B, of a holder B', to which the detachable barrel is attached, and a hammer M, mainspring N, and sear O, attached to the holder B', substantially as set forth.

9. The combination, with a gun provided with a stock and a permanent barrel, of a detachable barrel, a holder to which the detachable barrel is attached, a hammer, sear, and mainspring attached to said holder, and a

trigger mechanism attached to the gunstock and adapted to operate the lock of the detachable barrel, substantially as set forth.

10. The combination, with a gun provided
5 with a permanent barrel, of a detachable
barrel B, a holder B', a hammer M, main-
spring N, and sear O, provided with a de-
pending arm, a trigger q, and a sliding bolt

S, whereby said sear is released, substantially as set forth.

Witness my hand this 31st day of July,
1886.

HENRY B. GORTON.
